CLAIM

The ornamental design for a page aligner for an open book or the like, as shown and described.

DESCRIPTION

FIG. 1 is a perspective view of a page aligner for an open book or the like embodying my new design;

FIG. 2 is a top plan view thereof;

FIG. 3 is a bottom plan view thereof;

FIG. 4 is a front elevational view;

FIG. 5 is a right side elevational view; and

FIG. 6 is a left side elevational view.
